XP D 18,653

UNITED STATES PATENT OFFICE.

GIULIO MARCHETTI, OF HALIFAX, COUNTY OF YORK, ENGLAND, ASSIGNOR
TO JOHN CROSSLEY & SONS, OF NEW YORK, N. Y.

DESIGN FOR A CHAIR-COVER.

SPECIFICATION forming part of Design No. 18,653, dated October 2, 1888.

Application filed September 6, 1888. Serial No. 284,706. Term of patent 3½ years.

To all whom it may concern:

Be it known that I, GIULIO MARCHETTI, a resident of Halifax, York county, England, have invented a certain new and original Design for Chair-Covers; and I do hereby declare the following to be a full, clear, and exact description of the same, such as will enable others skilled in the art to which it appertains to make and use the design, reference being had to the accompanying photograph, which forms part of this specification.

My invention relates to a design for chair-covers; and it consists in a novel ornamentation of the filling or body design of the cover, substantially as hereinafter described, and pointed out in the claim.

The accompanying photograph is a plan view of the chair-cover embodying my design.

A represents the filling or body design of

the chair-cover, which consists of a conventional branch with leaves, upon which rests a bird, the whole of eccentric Indian character. Three bands, B C D, form the border surrounding the filling A. The inner band, B, consists of conventional Indian plants and shrubs alternating regularly with pieces of ornament. The center band, C, is a continuous scroll of Indian work representing branches, leaves, and blossoms, while the outer band, D, represents a watered or waved effect, which, like band C, is conventional in treatment.

I claim—

The design for chair-covers represented in the accompanying photograph.

GIULIO MARCHETTI.
